UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

MINING MACHINE.

Application filed April 17, 1920. Serial No. 374,746.

To all whom it may concern:

Be it known that I, CHARLES E. DAVIS, a citizen of the United States, residing at Chicago, in the county of Cook and State of Illinois, have invented an Improvement in Mining Machines, of which the following is a specification.

My invention relates to mining machines, and more particularly to mining machines 10 of the type commonly known as the continuous cutter coal mining machine, which is adapted to be moved laterally across the wall of the mine to cut a horizontal kerf thereunder.

15 The object of the present invention, generally stated, is to provide improved means for feeding and guiding a mining machine of the above description for performing the cutting operation.

20 Mining machines of the continuous cutter type are particularly adapted for use in the room and pillar system of mining. They are usually fed to the work by means of a flexible draft device, such as a rope, chain, 25 or the like, which is anchored at its free end in the desired direction of travel, and wound on a drum driven by the motor. A second draft device is anchored in the opposite direction to the first, and paid out from the 30 rear end of the machine frame as the machine advances. A suitable retarding means is provided for the purpose of controlling the second draft device in order to maintain a proper position in relation to the mine 35 wall.

In the embodiment herein described, which illustrates one of several forms which my invention may take, I have shown two rope drums, one of which is adapted to be 40 normally driven, and the other of which is provided with a retarding means comprising a friction-controlled releasing device. However, I find that certain additional advantages in the guiding and manipulation 45 of the machine are obtained by a construction in which the normal functions of the two drums may be mutually reversed at certain times, particularly as the machine is approaching and leaving the normal cutting 50 position. Accordingly, in the present invention, I provide means whereby the drum which is normally the tail-rope drum may be positively driven by the motor, while the other drum is simultaneously disconnected 55 from the motor, and allowed to be released

by an adjustable friction device. I also provide variable speed mechanism affording operative connection at will between the motor and either of the two drums.

As will hereinafter more fully appear, the 60 main purpose in thus reversing the functions of the rope drums is to facilitate the movement of the machine as it is being applied to, and withdrawn from, the working face, and to eliminate certain replacements 65 of the rope anchors which are necessary with the ordinary type of machine, thereby affording a more continuous movement of the machine. A distinction must therefore be made between the temporary reversal of 70 the functions of the drums for the purpose stated above, and a complete reversal of the direction of cutting. As is well known to those skilled in the art, the normal direction of cutting is determined by the direction of 75 movement of the cutter chain; that is to say, the side of the cutter chain in cutting engagement with the work, always moves towards the machine, and drags the cuttings out of the kerf. In the event that it is desired to reverse 80 the direction of movement of the machine, and cut from left to right instead of right to left, it is necessary to reverse the direction of movement of the cutter chain, which operation usually involves reversing the cutter bits, (or the chain), rearranging the control ropes, and reversing the direction of rotation of the motor and driving mechanism. Altho one of the secondary features of the 85 present invention is the provision of mechanism whereby such a complete reversal may be accomplished if desired, yet it will be seen that for the primary purpose stated above, the functions of the drums are reversed temporarily without affecting any 90 change in the normal direction of movement of the cutting operation.

Furthermore, the present invention should be distinguished from that class of machines 100 which also have driving connections with both feed and tail-rope drums, but in which the drums are simultaneously driven in opposite directions so that the tail-rope is paid out at the same rate that the feed rope is wound in, for the purpose of maintaining a 105 right-angled relation of the machine to the face during the cutting operation. As will appear in the description of the operation of the present invention, the manipulation 110 of the machine while approaching and leav-

ing the work, usually requires respective rates of movement of the two drums which vary so greatly, that a device in which the drums are driven simultaneously as above described would be useless and inoperative for the purpose of the present invention.

Other objects of the invention will appear from time to time as the description proceeds.

10 The invention consists in the combination, construction, and arrangement of parts as will hereinafter be described in connection with the accompanying drawings, and more particularly defined in the appended claims.

15 In the drawings, Figure 1 is a plan view of the machine in normal cutting position.

Figure 2 is a rear elevation of the driving mechanism, drawn to a larger scale than Figure 1.

20 Figure 3 is a right side elevation of the driving mechanism drawn to the same scale as Figure 2.

Figure 4 is an enlarged plan view of the mechanism shown in Figure 3, showing some 25 of the details in section.

Figure 5 is a vertical transverse cross section of a rope drum taken on line 5—5 of Figure 4.

30 Figure 6 is a cross section taken on line 6—6 of Figure 5.

Figure 7 is another cross section taken on line 7—7 of Figure 5.

Figure 8 is a cross section taken on line 8—8 of Figure 4.

35 Figures 9 and 10 are detailed views of the friction ring pawl.

Figures 11 and 12 are detailed views of the gear ring pawl.

40 Figures 13 to 18 inclusive, are diagrammatic views showing the machine and control ropes in various positions during the cutting operation.

My invention is shown as applied to a mining machine having a main frame A, and a cutting element 1 projecting therefrom. This cutting element is preferably provided with an endless cutter chain of the usual pattern, which is driven by the motor B, to cut a horizontal kerf in the mine wall 45 as the machine advances. Figure 1 shows the arrangement of the machine and control ropes during the normal cutting operation across the working face. A rope 2 is adapted to be wound on a drum 3, mounted on the left side of the machine frame A. Said rope passes from said drum over a pulley 4 adjacent the front end of the machine frame, and thence to a suitable anchor 5, fixed at a distance from the machine, and 50 near the working face along which the machine is to be moved. A second rope 6 is anchored at the opposite end of the working face, and is led over suitably arranged pulleys 7 and 8, at the rear end of the machine frame, to a second drum 9, on the right side

of the machine. The arrangement is such that in the normal cutting position illustrated in this figure, the rope drum 2 is connected thru driving mechanism, to be hereinafter described, to the motor B. The opposite drum 9 is disconnected from the driving mechanism, and during the normal cut across the face, is released at a rate substantially the same as the rate of take-up on the rope 2, by means of an adjustable friction band device 10 on the drum 9. The purpose of the rope 6 is to restrain the movement of the rear end of the machine, and maintain the proper angular relation of the cutter bar of the working face.

Referring now more particularly to the novel features of my invention, means are provided for reversing the normal functions of the two drums above described, whereby the drum 9 may have a driving connection with the motor, and the other drum 3 may be released thru a friction device 11 similar to the friction device 10 above described. The functions of the two drums being therefore mutually reversible, I find it preferable to make the drums identical in construction.

The main elements of the driving mechanism for drums 3 and 9 comprise a longitudinal shaft 12 geared to the motor B, a worm gear 13 actuated by said longitudinal shaft, a variable speed mechanism 14, and an endwise movable shaft 15 driven by said variable speed mechanism, and provided with interlocking clutches 16 and 17 on opposite ends thereof. The driving connection between clutch 16 and the drum 3, comprises a shaft 18, driving pinion 19 and gear ring 20 on said drum. The driving connection between clutch 17 and the drum 9, comprises a pinion 21, idler gear 22, and a gear ring 23 on the latter drum. The purpose of the idler gear 22 is to drive said drum in a direction opposite to that of the other drum 3.

The variable speed mechanism 14 illustrated, is preferably of the planetary type which may be of any approved construction, provided with an external friction band 14^a, and a friction adjusting handle 14^b, for the purpose of transmitting variable speeds to the shaft 15. Details of this gear need not be described excepting to indicate a clutch member 24 feathered on the shaft 15, and provided with clutch jaws 25, 25 adapted to be engaged either with a high speed member 26, or low speed member 27 of the planetary gear 14. The clutch member 24 is provided with a shifter yoke 28, and a control handle 29 attached thereto. Altho I have shown a planetary gear variable speed mechanism, it will be understood that so far as the broad features of my invention are concerned any equivalent variable speed device may be substituted therefor.

The endwise movable shaft 15 extends

thru the speed reducing mechanism 14 and worm gear 13 to form an axial bearing therewith. The clutch 16 on the left end of said shaft comprises an annular flange 5 30 on said shaft, provided with clutch jaws 31, 31 adapted to engage with corresponding clutch jaws 32, 32 on the connecting shaft 18 extending to the left hand drum 3. The shaft 15 is also provided with a recess 10 33 in which a reduced portion 34 of the connecting shaft 18 extends, for the purpose of maintaining the two shafts in alignment with each other.

The clutch 17 for connecting the shaft 15 to the right hand drum 9 is located adjacent the interior face of the pinion 21 on the right hand side of the machine. Said clutch comprises a sleeve 35 fixed to the shaft 15 and extending thru the pinion 20 21 to form an axial bearing therewith clutch jaws 36, 36 are carried by said sleeve, and are adapted to engage corresponding clutch jaws 37, 37, preferably formed integral with the pinion 21. Means 25 for shifting the shaft 15 comprises a shifter yoke 38 mounted on the sleeve 35, provided with a shifter arm 38^a, which is operated by a suitable control handle 39, (see Fig. 2). In the position shown in Figures 2, 3 and 30 4, the shaft 15 is in neutral position, that is to say, clutches 16 and 17 are both disengaged. It will be seen that if the control handle 39 is moved downwardly, the shaft 15 will be moved longitudinally so 35 as to engage the clutch 16 to form a driving connection with the rope drum 3. On the other hand, if the control handle is moved upwardly, the shaft will be moved in the opposite direction, clutch 16 will be disengaged, and the opposite clutch 17 will become engaged to form a driving connection with drum 9.

The rope drums 3 and 9, as hereinbefore pointed out, are preferably identical in construction, so that a detailed description of one of the drums will apply to both. Means whereby each drum is automatically engaged and disengaged from its respective driving gear and friction device, comprise 45 a pair of ratchet and pawl devices, details of which appear in Figures 5 to 12 inclusive. Drum 3 for instance, comprises a rim or body portion 3^a, a web 3^b, and a hub 3^c mounted on a suitable bearing pin 3^d, fixed on the machine. A driving gear ring 20 is loosely mounted on the drum body 3^a, and is provided with a plurality of notches 40, 40, spaced about the interior surface thereof. (See Figs. 7 and 8.) A pawl 50 41 is mounted on a rocking pin 42, and extends thru a suitable aperture in the drum rim 3^a to engage with the notched surface of the gear ring 20. The rocking pin 42 bears at one end in a lug 43 projecting inwardly from the periphery of said

drum body 3^a, and extends thru the web 3^b of the drum. A dog 45 is fixed on the pin 42 adjacent the lug 43, said dog having an arm 45^a extending over said lug and being adapted to engage the pawl 70 41. A handle 46 is fixed on the outer end of the rocking pin 42, and in a position suitable to be manipulated by hand. A spring 47 is attached at one end of said handle, and at the other end to the periphery of the drum at a point on the radial line passing thru the axis of the pin 42. The dog 45 and handle 46 are substantially 75 in longitudinal alignment with each other on the rocking shaft 42, so that the tension 80 of the spring 47 is transmitted to the pawl 41 thru the dog 45, which serves to maintain the pawl in engaged relation against the notched surface of gear ring 20. The friction device 11 is mounted adjacent the 85 gear ring 20, and comprises the friction ring 50, friction band 48 and friction adjusting handle 49 of the usual type. In the form illustrated, the friction ring 50 is loosely 90 mounted on the drum rim 3^a, and is provided with a ratchet and pawl device similar to that hereinbefore described in association with the gear ring 20. Said ratchet and pawl device comprises notches 51, 51, on the friction ring, pawl 52, dog 53, rocking pin 54, handle 55 and spring 56.

It will be observed that the friction pawl 52 is normally inclined to the friction ring 50 in the same direction as the driving pawl 41, as shown in Figure 5. When the pawls are in this position, and gear ring 20 is driven by the motor in the direction indicated by the arrow, the pawl 41 becomes engaged in one of the notches 40, (see Fig. 8) and the drum is carried with the gear ring to wind up the rope 2. When the driving connection to the motor is disengaged, the drum may move in the opposite direction until the friction pawl 52 engages with a notch 51 in the friction ring 50. The rope 100 2 can then be paid off the drum only against friction imposed by the friction band 48, which may be regulated by the handle 49 in the usual manner. If power is again applied to the gear ring 20, it will 105 move in a direction to wind up the rope. The friction pawl becomes released as the drum is rotated in the opposite direction, so that the drum is driven independent of the friction device, in the same manner as before. It will thus be seen, that the drum may alternately be driven by the motor in one direction, or be released against friction in the opposite direction.

Whenever it is desired to reverse the direction of driving the drum 3, either to reverse the direction of cutting, or for any other purpose, the pawls 41 and 52 may be rocked about their axes by the manipulation of the handles 46 and 55, so that the 110 115 120 125 130

opposite ends of the pawls are moved into engaging relation with the driving gear ring 20 and friction ring 50, respectively. The springs 47 and 56 are rocked over the centers of their respective pins, so as to exert the desired tension in each pawl in either position thereof.

The purpose of the ratchet and pawl device associated with the driving gear as 10 above described, is to provide means whereby the drum may be rotated by hand in the same direction as the direction of driving, when desired. Altho the drum may also be rotated by hand when the driving clutch 15 is disengaged, I prefer to provide the ratchet and pawl device so as to disengage the gearing intermediate the drum and its respective clutch mechanism, thereby reducing the friction to a minimum when the 20 drum is rotated in this manner.

The ratchet and pawl device associated with the friction ring 50 allows the drum to be rotated freely by the driving means in the direction to wind the rope on the 25 drum, but engages the drum with said friction device as the rope is unwound or withdrawn from said drum.

An extensible handle 60 is provided on each drum, which handle is normally retained in retracted position by a spring 61 and plunger 62, but which may be pulled out beyond the face of the drum whenever it is desired to wind or unwind the drum by hand. When it is desired to actuate the 35 drum by hand, the clutch 17 is disengaged, and the friction band 48 released, so that the drum is free to be rotated in either direction.

Some of the advantageous features of a 40 mining machine constructed in accordance with my invention, may be best understood by reference to Figures 13 to 18 inclusive, which illustrate a so-called room and pillar mine, and show the machine in various 45 positions incident to the cutting operation. The mining machine is usually brought into a room on a truck, and is unloaded at a point a short distance from the working face 63 as shown in Figure 13. From this 50 position it is drawn to one corner of the room under its own power by means of the rope 6, associated with the right hand drum 9, which rope is anchored in a suitable position, as for instance, point 64 in the right 55 hand corner of the room adjacent the side wall or face 65. In the present description, the cut is shown as proceeding from right to left along the working face 63, but it will be understood that the cutting operation 60 may be from the opposite corner, and proceed from left to right, if desired. With the rope 6 anchored in position as described, it is led over pulley 66, or a similar appropriate arrangement of pulleys for 65 guiding the machine to the face, and is

wound on drum 9 to drag the machine into position. The machine is then ready for making its initial cut into the face, which cut is usually made in a direction substantially longitudinal of the cutter bar, 70 and is known as the sumping cut. In making the sumping cut, it is necessary to project the machine forwardly into the face by means of the power ropes, and at the same time control the movement of the machine so that the machine will be maintained at the desired angle to the wall. Rope 2 may therefore be anchored at some point to the left of the machine, preferably at point 5, which position is also suitable 80 for the anchor when the transverse cut is thereafter made across the face. In this position, the rope 2 may be led around pulley 67, if desired. When the ropes are thus anchored and the sumping cut is progressing, it will be seen that the rope 6 tends to swing the rear end of the machine to the right. Therefore, the friction device 10 on the drum 3 is adjusted so that the rope 2 restrains this lateral movement of the machine, and gives the desired line of advance 90 into the face.

When the sumping cut is completed, and the machine is in position ready to make the transverse, or lateral cut, as shown in 95 Figure 1, the rope 6 is changed to its normal position about pulleys 7 and 8 at the rear end of the frame, the rope 2 is changed to its normal position about pulley 4 at the front end of the frame, and the transverse cut is then made across the face, as shown in Figure 1, using rope 2 as the feed-rope, and rope 6 as the tail-rope.

It will be understood however, that the procedure in making the sumping cut as 100 above described, may be deviated from in several details, particularly in regard to the arrangement of the ropes about the pulleys, depending upon the working conditions encountered as each cut is made. For instance, it may be desirable to place the anchor 64 somewhat farther away from the face, in which case the rope 6 would be changed to the rear pulleys 7 and 8 at the beginning of the sumping cut instead of at the completion of this cut. It also may be possible under some conditions, to train the rope 2 about the front pulley 4 at the beginning of the sumping cut, and thus dispense 110 with the necessity of changing the feed rope when the transverse cut is commenced. The most convenient arrangement of ropes may be chosen by the operator as he desires. The essential and novel feature however, is that whereby the rope 2 may be anchored in one 115 position, to act first as a restraining, or tail-rope, during the sumping cut, and may then be used in its normal function as a pulling, or feed rope during the transverse cut, without changing the position of the anchor 5 120 130

thereof. Similarly, the rope 6 is first used as a pulling, or feed-rope, both in dragging the machine to the face, and in making the sumping cut, and is then utilized in its 5 normal function as a restraining, or tail-rope during the transverse cut, without changing the position of the anchor 64, thereof.

When the transverse cut is completed, as 10 in Figure 16, it has heretofore been necessary to change the position of the feed rope anchor 64 to a second position farther removed from the face in order to withdraw the machine rearwardly and thus finish the 15 cut in a line with the left hand wall 68. With my machine, it is not necessary to replace the anchor in this manner, as it will be seen that by the application of power to the rope 6, when the machine is positioned 20 at the end of the cut as shown in Figure 16, the rear end of the machine will be swung to the right. The right hand front corner of the machine frame will then fulcrum at point X on the mine face 63, while the friction 25 device on the rope 2 may be manipulated so that the cutter arm 1 will complete the cut along the left wall 68, and finally be withdrawn therefrom. This cut may tend to be slightly curved, somewhat as shown in 30 Figures 17 and 18 but by proper manipulation of the friction device 10, I find that the cut along the side face may be made straight enough for practical purposes. When the finishing cut illustrated in Figure 17 is completed, the tail-rope 6 is still in position to 35 continue its pull on the machine to withdraw it substantially to the center of the room, from where it may be again loaded on the truck to be withdrawn from the room. 40 As pointed out in connection with the foregoing description of the sumping cut, it will also be seen that the specific arrangement of ropes over the pulleys may be changed during the finishing cut, depending 45 upon working conditions, but the essential feature afforded by a machine constructed in accordance with my invention, is that whereby the finishing cut may be made without replacing either of the anchors, and furthermore, the machine may be withdrawn 50 to the center of the room by means of the rope 6, which is an added saving in time ordinarily required when the rope 2 must be re-anchored and used for this purpose. 55 It will be borne in mind that all of the above operations may be accomplished at any desired speed, by means of the speed reducing mechanism 14, which is adapted to provide a wide range of speeds to either 60 rope drum as it is being driven. Such a combination of a pair of drums, both of which are provided with a variable speed driving connection and an independently controlled friction device, affords an arrangement whereby the machine may pull 65

itself to the face, make the sumping cut, make the transverse cut, and the finishing cut and be withdrawn to the center of the room, with a minimum number of settings of the anchors, and affords thereby a substantially continuous progress of the machine from the beginning to the end of the entire cutting operation. 70

A further advantage is the construction in which the functions of the feed and tail-rope may be reversed at any time during the normal cut across the face, for the purpose of dislodging or cutting around extremely hard material which often forms an obstruction to the progress of mining 75 machines of this class. By suitable whipsawing or rocking movement of the machine when such obstructions are encountered, it is often possible to cut behind or around such obstructions, and in some cases entirely remove them. 80

Another advantage of this machine is the construction whereby the movement of the machine is capable of being completely reversed, so that the cutting operation may be 85 carried thru either from right to left, or from left to right. Such a complete reversal may be accomplished by reversing the cutting elements on the cutter bar, rocking the pawls 41 and 52 on both rope drums, and 90 reversing the direction of rotation of the motor. 95

Having described my invention what I claim as new and desire to cover by Letters 100 Patent, is:

1. In a mining machine of the class described, the combination of a motor, and two flexible draft devices, each adapted to be driven in one direction by said motor and having means independent of said driving means for retarding each of said draft devices when moved in the other direction. 105

2. In a mining machine of the class described, the combination of a motor, two flexible draft devices, mechanism including a clutch affording an operative connection between said motor and each of said draft devices, and means for retarding each of said draft devices when its respective clutch is disengaged. 110

3. In a mining machine of the class described, the combination of a motor, two flexible draft devices, mechanism including interlocking clutches, each affording an operable connection between said motor and one of said draft devices, and means for retarding each of said draft devices when its respective clutch is disengaged. 115

4. In a mining machine of the class described, the combination of a motor, a flexible draft device having operative connection with said motor whereby said draft device may be driven in one direction, a retarding device, and means for automatically connecting said retarding device with said 120 125 130

- draft device when the latter is moved in the opposite direction.
5. In a mining machine of the class described, the combination of a motor, two flexible draft devices each having operative connection with said motor whereby said draft device may be driven in one direction, a retarding device associated with each draft device, and means for automatically connecting said retarding devices with their respective draft devices when the latter are moved in the direction opposite to that in which they are driven.
6. In a mining machine of the class described, the combination of a motor, two control devices, each associated with a draft means, and a driving connection between each of said control devices and said motor including interlocking clutches whereby one of said control devices is free to rotate independent of said driving mechanism when the opposite device is being driven, and a retarding device associated with each of said control devices independent of said driving mechanism.
7. In a machine of the class described, the combination of a motor, two drums, each associated with a flexible draft means, and a driving connection between each of said drums and said motor including interlocking clutches whereby one of said drums is free to move independent of said driving mechanism when the opposite drum is being driven, a retarding device associated with each of said drums, and means for automatically engaging each retarding device with its respective drum when the latter is moved in a direction opposite to that in which said drum is adapted to be driven.
8. In a machine of the class described, the combination of a motor, a drum, a flexible draft device adapted to be wound on said drum, a driving connection between said motor and said drum comprising a change speed mechanism and a clutch, whereby said drum may be driven in one direction, a retarding device and means for automatically engaging said retarding device with said drum when the latter is moved in the opposite direction.
9. In a machine of the class described, the combination of a motor, two drums, each associated with a flexible draft means, a variable speed mechanism connected with said motor, a clutch interposed between each of said drums and said variable speed mechanism, means for actuating said clutches simultaneously and a retarding device associated with each of said drums.
10. In a machine of the class described, the combination of a motor, a variable speed mechanism connected with said motor, two drums each associated with a flexible draft means, driving mechanism intermediately each of said drums and said variable speed mechanism including interlocking clutches, and a retarding device independent of said driving means associated with each of said drums.
11. In a machine of the class described, the combination of a motor, two drums, each associated with a flexible draft means, a variable speed mechanism connected with said motor, a longitudinally movable shaft driven by said variable speed mechanism and provided with two clutch members, each adapted to form a driving connection with one of said drums, and means for moving said shaft into a plurality of positions.
12. In a machine of the class described, the combination of a motor, two drums, each associated with a flexible draft means, driving mechanism for said drums, comprising a planetary gear speed reducing mechanism, and a longitudinally movable shaft concentric with, and extending thru, said speed reducing mechanism, a plurality of clutch members on said shaft, corresponding clutch members connected with each of said drums, and means for moving said shaft longitudinally into a plurality of positions.
13. In a machine of the class described, the combination of a frame, a motor, two drums, each associated with a flexible draft means, a pinion having driving connection with one of said drums and supported by said frame, a longitudinally movable shaft driven by said motor, said shaft being mounted concentrically with, and having bearing in, said pinion, a clutch on said shaft affording operative connection with said pinion, a second clutch on said shaft having operative connection with the other of said drums, and means for moving said shaft longitudinally to actuate said clutches.
14. In a machine of the class described, the combination of a motor, two drums, each associated with a flexible draft means, a pinion having driving connection with one of said drums, a bearing for said pinion mounted on said frame, a longitudinally movable shaft mounted concentrically with said pinion, a sleeve fixed on said shaft having an external bearing in said pinion, clutch means associated with said sleeve adapted to have driving engagement with said pinion, a second clutch on said shaft affording a driving connection with the other of said drums, and means for shifting said shaft longitudinally.
15. In a machine of the class described, a combination of a frame, a motor, two drums, each associated with a flexible draft means, a longitudinally movable shaft having driving connection with said motor, a second shaft having operative connection with one of said drums, clutch means interposed between said shafts, a second clutch afford-

ing driving connection with the other of said drums, and means for moving said shaft longitudinally.

16. In a machine of the class described, the combination of a driving means, a drum associated with a flexible draft means having operative connection with said driving means, a clutch, a frictionally controlled device adapted to rotate with said drum, and means automatically affording an operative connection between said frictionally controlled device and said drum in one direction of movement of the latter.

17. In a machine of the class described, a combination of driving means, a drum associated with a flexible draft means having operative connection with said driving means, a clutch, a frictionally controlled device adapted to rotate with said drum, and a ratchet and pawl device affording an operative connection in one direction between said drum and said friction device.

18. In a machine of the class described, a combination of a driving means, a drum associated with a flexible draft means having operative connection with said driving means, a clutch, a frictionally controlled device adapted to rotate with said drum, and a reversible ratchet and pawl device affording an operative connection between said drum and said friction device in either direction.

19. In a machine of the class described, the combination of a driving means, a drum associated with a flexible draft means, a gear loosely mounted on said drum and adapted to have operative connection with said driving means, a ratchet and pawl device associated with said drum whereby said drum may be driven in one direction, a frictionally controlled member also loosely mounted on said drum, and a second ratchet and pawl device affording an operative connection between said drum and said friction device in the opposite direction.

20. In a machine of the class described, the combination of a driving means, a drum associated with a flexible draft means, a gear loosely mounted on said drum and adapted to have operative connection with said driving means, a reversible ratchet and pawl device associated with said drum whereby said drum may be driven in either direction, a frictionally controlled member also loosely mounted on said drum, and a second reversible ratchet and pawl device affording an operative connection between said drum and said friction device in either direction.

21. In a mining machine, the combination of a motor, a variable speed mechanism having operative connection with said motor, a rotatable member driven by said motor, a rotatable member driven at different speeds by said variable speed mecha-

bers each adapted to have operative connection with said rotatable member to be driven in one direction, and means for retarding said draft members when rotated in the opposite direction.

22. In a mining machine, the combination of a motor, a variable speed mechanism having operative connection with said motor, a rotatable member driven by said variable speed mechanism, two draft members, means affording operative connection between said rotatable member and both of said draft members comprising a pair of interlocking clutches, and means for retarding each of said draft members.

23. In a mining machine, the combination of a motor, a variable speed mechanism having operative connection with said motor, a rotatable member driven by said variable speed mechanism, two draft members each adapted to have operative connection with said rotatable member to be driven in one direction, and means for automatically retarding said draft members when moved in the opposite direction.

24. In a mining machine, the combination of a motor, a variable speed mechanism having operative connection with said motor, a rotatable member driven by said variable speed mechanism, two draft members each adapted to have operative connection with said rotatable member to be driven in one direction, means for automatically retarding said draft members when moved in the opposite direction, and means for manually controlling said retarding means.

25. In a mining machine of the class described, the combination of a motor, a flexible draft device having operative connection with said motor whereby said draft device may be driven in one direction, a retarding device, means for automatically connecting said retarding device with said draft device when the latter is moved in the opposite direction, and means for manually controlling said retarding device.

26. In a mining machine of the class described, the combination of a motor, two flexible draft devices each having operative connection with said motor whereby said draft device may be driven in one direction, a retarding device associated with each draft device, means for automatically connecting said retarding device with their respective draft device when the latter is moved in the direction opposite to that in which it is driven, and means for manually controlling each of said retarding devices.

27. In a mining machine, the combination of a frame, a motor, a variable speed mechanism having operative connection with said motor, a rotatable member driven at different speeds by said variable speed mecha-

nism, two rotatable draft members on opposite sides of said frame, each adapted to have operative connection with said rotatable member to be driven in opposite directions with respect to each other, and means for retarding each of said rotatable draft means when moved in a direction opposite to that in which it is driven.

28. In a mining machine, a frame provided with a longitudinally extending cutting element, a motor on said frame, variable speed mechanism having operative connection with said motor, a shaft driven selectively by said variable speed mechanism at a plurality of speeds and extending transversely of said frame, two rotatable draft members arranged at opposite sides of said frame and rotatable on transverse axes, each having operative connection with said shaft,

and means for retarding said rotatable draft members.

29. In a mining machine, a frame provided with a longitudinally extending cutting element, a motor on said frame, variable speed mechanism having operative connection with said motor, a shaft driven selectively by said variable speed mechanism at a plurality of speeds and extending transversely of said frame, two rotatable draft members arranged at opposite sides of said frame and rotatable on transverse axes, each having operative connection with said shaft, one of said rotatable members being driven through an idler gear in a direction opposite to that in which the other rotatable member is driven, and means for retarding said rotatable draft members.

CHARLES E. DAVIS.
